(57) **CLAIM**

The ornamental design for a low profile surface mounted light fixture, as shown and described.

DESCRIPTION

FIG. 1 is a perspective view of a low profile surface mounted light fixture, showing my invention.

FIG. 2 is a top plan view of the invention;

FIG. 3 is a bottom plan view of the invention;

FIG. 4 is left side elevation view of the invention taken from the left end of FIG. 1;

FIG. 5 is right side elevation view of the invention taken from the right end of FIG. 1;

FIG. 6 is a side elevation view of the invention taken from the top side of FIG. 1; and,

FIG. 7 is a side elevation view of the invention taken from the lower side of FIG. 1.

An optional cable with connector is shown in broken lines for the purpose of illustrating environmental structure only and forms no part of the claimed design.
